UNITED STATES PATENT OFFICE

154,325

DESIGN FOR A DISPENSING MACHINE

Henry T. Roberts, Chicago, Ill., assignor to
United States Vending Corporation, Chicago,
Ill., a corporation of Delaware

Application January 22, 1948, Serial No. 143,985

Term of patent 3½ years

(Cl. D52—3)

To all whom it may concern:

Be it known that I, Henry T. Roberts, a citizen of the United States, residing at Chicago in the county of Cook and State of Illinois, have invented a new, original, and ornamental Design for a Dispensing Machine, of which the following is a specification, reference being had to the accompanying drawings, forming a part thereof.

Fig. 1 is a perspective view of a dispensing machine embodying my new design.

Fig. 2 is a plan view of the machine shown in Fig. 1.

Fig. 3 is a front elevational view.

Fig. 4 is a side elevational view.

I claim:

The ornamental design for a dispensing machine, substantially as shown.

HENRY T. ROBERTS.
